UNITED STATES PATENT OFFICE

117,833

DESIGN FOR A FOLDING BOX

Margaret Laine, New York, N. Y.

Application August 4, 1939, Serial No. 86,470

Term of patent 3½ years

To all whom it may concern:

Be it known that I, Margaret Laine, a citizen of Germany, residing at New York, in the county of New York and State of New York, have invented a new, original, and ornamental Design for a Folding Box, of which the following is a specification, reference being made to the accompanying drawing, forming part thereof.

in set-up position with the cover partly raised and with the cord tied at front, showing my new design.

Figure 2 is a top plan view of the box shown in Figure 1, in collapsed position.

I claim:

The ornamental design for a folding box, as shown.

MARGARET LAINE.
